CLAIM

We claim the ornamental design for a generator set housing, as shown and described.

DESCRIPTION

FIG. 1 is a top, front, left isometric view of a first embodiment of a generator set housing showing our new design;

FIG. 2 is a top, rear, right isometric view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a right side elevational view thereof;

FIG. 8 is a left side elevational view thereof;

FIG. 9 is a top, front, left isometric view of a second embodiment of a generator set housing;

FIG. 10 is a top, rear, right isometric view thereof;

FIG. 11 is a top plan view thereof;

FIG. 12 is a bottom plan view thereof;

FIG. 13 is a front elevational view thereof;

FIG. 14 is a rear elevational view thereof;

FIG. 15 is a right side elevational view thereof; and,

FIG. 16 is a left side elevational view thereof.

The broken lines in the figures illustrate portions of the generator set housing that form no part of the claimed design.

1 Claim, 16 Drawing Sheets
